UNITED STATES PATENT OFFICE

ARTHUR THOMAS, OF THORNTON HEATH, AND RICHARD FITZ POWER, OF HAMPSTEAD, LONDON, ENGLAND, ASSIGNEES TO THE ACCOUNTING & TABULATING CORPORATION OF GT. BRITAIN LIMITED, OF LONDON, ENGLAND

PUNCHING OR LIKE MACHINE

Application filed August 9, 1929, Serial No. 384,601, and in Great Britain August 20, 1928.

This invention relates to a punching machine for record cards or the like and has for its object to accelerate the action of punching machines and in the case of hand operated 5 perforating machines for record cards, for instance, as used in statistical machines, to provide a construction in which the key touch is made more suitable for an operator, errors are substantially eliminated, and it is cheaper 10 to manufacture; at the same time to provide a punching or perforating machine in which the card is visible immediately before punching and only a small part, actually, a column, on the card obscured during a punching operation, and a still further object is to produce a punching machine incorporating a magazine from which cards to be punched are supplied to the punch, as a compact entity.

A method of operating punches of a card 20 perforating machine according to the invention consists in transmitting effort to the punches from an actuating member during one movement in one direction thereof, so that the punching and return stroke of the 25 punches are effected during one stroke of the actuating member.

The invention further consists in a method 30 of operating punches of a card perforating machine wherein effort is transmitted to the punches from a striker by interposing a light selecting member in the path of the striker, and preferably the striker is reciprocated by effort transmitted from an actuating member during one movement in one direction 35 only whereby a maximum speed for the striker, and, therefore, a quick resetting of the machine, is attained, and the whole of the period of the return stroke of the key is available for the travel of the card to the next position.

A record card punching or perforating machine operating according to the present invention includes means for operating at will one of a series of punches by a striker 45 common to all the punches on the interpositioning between the striker and the corresponding punch of a light selector bar moved by selector mechanism. Supposing the selector mechanism comprises a keyboard for moving the selector bars, there will be a com-

mon striker operated mechanism which actuates a punch by a light selecting bar being interposed between the striker and punch by a key. Thus, instead of it being necessary to make rigid punch operating levers connecting the individual keys to their respective punches, it is only required to provide a light connection from the key to the punch and the care necessary in the construction of the actual punching mechanism can be concentrated 55 on the common mechanism with its single connection.

Further, by the use of a light selecting bar which needs only a flick to dispose it in effort transmitting position from a striker to 65 a punch, great flexibility of design is attained, that is to say, that supposing a key action is employed the keys need not directly operate the selector bars but may operate intermediate members so that the control from 70 the key to the selector may pass through a large angle, as for example, a right angle, as hereinafter more particularly described.

Preferably, the striker is so designed that immediately after the commencement of its 75 operation it stands in the path of the selector bars not operated, thereby the machine is locked against a subsequent operation until the accurate completion of the striker withdrawal stroke.

Conveniently, the striker is mounted on a reciprocating member positively moved through a complete reciprocation, i. e., to strike and withdraw during one movement in one direction of an actuating member. The 85 actuating member may be an intermittently rotated member operated by a pawl at predetermined intervals, or it may be in the form of a reciprocating member, in the latter case in accordance with the invention the complete 90 operation of the striker is attained during the movement in one direction of the reciprocating member.

In another form the striker may be carried by the sheath of an eccentric rotated through 95 360° by means of a pawl and ratchet device. The pawl may have two operative faces and the ratchet co-operating lateral abutments e. g. pins, disposed so that the movement of the ratchet communicated to the sheath is 100

effected by a variable effort, which is at a maximum, at about half travel of the ratchet.

In another form the eccentric may be driven by means of a pinion, connected in the manner of a free wheel to the eccentric, the actuating member in this case being in the form of a rack, the free wheel connection permitting an inoperative return stroke of the rack immediately after a punching operation.

If the punches are arranged vertically and of sufficient weight, they may be permitted to fall by gravity alone on the withdrawal of the striker, but in order to assure as rapid as possible a clearing of the punch from the card the striker is caused to positively return the punch immediately after a punch operation.

To this end the punches may be freely sliding members each formed with a head or some other lug or projection, which may be adjustable on the punch, the striker being formed to embrace the head or equivalent projection to positively impart the working and withdrawal strokes of the punches.

By utilizing freely sliding members no springs are employed to return the punches, consequently the operation will become lighter as the machine becomes freer running, that is to say, the machine will improve and not deteriorate during use.

In operation, therefore, of a striker mechanism according to the invention, the striker in its upstroke engages the projected end of a selector bar, pushes this selector bar up with the respective punch for a distance necessary to assure the punching operation by the punch and then pulls down the punch and the selector bar back to initial position, and thereafter the selector bar is withdrawn again to resetting position when the operating key for the bar—supposing a key action is employed—would be reset as hereafter explained.

Supposing, therefore, the bar is initially horizontal during the striking movement, its free end is moved upwardly with the striker. To permit this movement the selector bar may be hinged at its end further away from the striker. Alternatively, the selector bar could be a reciprocal member with the end which is introduced between the striker and its respective punch as an articulated extremity to the selector bar. Alternatively, the selector bar may be flexible to permit the distention during the operation of the striker.

A punch operating mechanism according to the invention is preferably used in combination with a key action carriage for feeding cards to the punch step by step between the punching operation. The combination may be characterized by a key action effecting the interpositioning of a light selector between the striker and punches, as hereafter particularly described.

With such an arrangement a novel method of operating punches obtains, such method

being characterized by the fact that the whole of the operation of perforating the card and withdrawing the punch from the hole is completed in the down stroke of a key, and the whole of the period of the return stroke of the key is available for the travel of the card to the next position.

An apparatus including in combination punch operating mechanism according to the invention and a key action carriage for feeding cards from the magazine to the punch, preferably includes a picker actuated by the carriage to move each card separately from the magazine to the carriage.

The keys may be formed with actuating cams adapted to positively push and retract the light selector bars from into and out of selecting position for the punches.

In a combined card feeding and punching mechanism according to the invention where in a key action carriage is employed for feeding cards to the punch, the key action is preferably utilized to operate the striker of the punch mechanism so that the punches are operated and withdrawn on the depression of a key, thereby the period of return stroke of the key is available for the movement of the carriage with the card through the next step permitted by the key action ready for the depression of the next key and the next consequential punching operation.

In such an arrangement and supposing the striker is operated through pawl and ratchet gear as hereinbefore explained, the return stroke of the pawl or equivalent actuating member for the striker is partially effected by impulse received from the carriage spring usually referred to as the "tension" of the carriage through the escapement which is connected to the key action as hereafter more fully explained, hence the tension of the carriage is utilized to effect not only the return of the punch actuating member but also the return of the key action to resetting position.

Preferably, the key action operating the escapement of the carriage produces the engagement of the check and actuating pawls with the carriage rack thereby positively holding the carriage rigidly during a punching operation.

In referring to a resetting position is meant, so far as regards key action or key operated mechanism, the position of the parts before any key is depressed.

The keys of the key action may be arranged in rows, each key of a row freely engaging a spring controlled rocking lever common to the row, the said rocking levers being connected to the striker gear, thereby on the depression of any key the striker is operated and the other keys are rendered inoperative. The said spring controlled rocking lever may directly operate the pawl or rack, whichever is employed of the striker actuating gear, or

alternatively operate a rock shaft carrying a toothed member engaging the striker pinion.

The punches are preferably aligned in a column by a narrow die plate slotted transversely for the introduction of cards for a punching operation whereby only a column of the cards being punched is obscured from view and the punch support may be formed 10 with a guide, e. g. in the form of a die or slot, for the card feeding carriage assuring correct vertical setting, the carriage preferably being also formed with a circular slide moving in a bearing assuring horizontal setting 15 of the carriage, thereby assuring correct presentation of a card to the said apparatus assuming the card is accurately presented to the carriage.

In order that the invention may be more 20 clearly understood preferred constructions will now be described with reference to the accompanying drawings by way of example, wherein is employed, in conjunction with a punch or perforator according to the invention for making holes in cards, a key action carriage card feeding mechanism so that the cards are punched as they are fed by the carriage step by step to the punches.

In the drawings:

30 Fig. 1 is a perspective view showing the complete machine parts, being broken away for the sake of clearness;

Fig. 2 is an end elevation of the machine the parts being in inoperative position;

35 Fig. 3 is a similar view to Fig. 2, only such parts being included as to show the striker raised as a result of a key operation and a punch displaced;

40 Fig. 4 is a side elevation of the parts in the position shown in Fig. 3;

Figs. 5, 6, 7 and 8 are detail views showing the operation of the striker by means of the mechanism shown in the construction illustrated in Figs. 1, 2 and 9;

45 Fig. 9 is a front elevation of the machine illustrated in Fig. 1;

Fig. 10 is a rear elevation thereof; and

Fig. 11 is a plan view.

50 In Figs. 9, 10 and 11 the card receiving device is shown collapsed against the machine.

Fig. 12 is a perspective view showing the modified arrangement for operating the light bars, and a modification of the light bar construction;

55 Fig. 13 shows in perspective view a modified arrangement for operating the striker;

Fig. 14 shows a further modification of such arrangement;

60 Figs. 15, 16 and 17 show in diagrammatic elevation a plan and end view respectively, a still further modified arrangement for operating the striker from a key action;

65 Figs. 18 and 19 are a perspective view and sectional elevation of a modified form of dog for use with a skip mechanism;

Fig. 20 is a front elevation of the carriage; of which

Fig. 21 is an end view, the parts of the carriage being in non-gripping position;

Fig. 22 is a rear elevation of the carriage 70 showing the parts in gripping position;

Fig. 23 is an end view thereof;

Fig. 24 is a central sectional elevation taken on the line XXIV—XXIV of Fig. 10;

Fig. 25 is a fragmentary rear view of the 75 card magazine showing the cradle collapsed for the reception of a batch of cards; and

Figs. 26 and 27 show in diagrammatic elevation and plan respectively a modified arrangement employing picker mechanism for 80 removing cards from the bottom of the pile.

In the drawings like reference numerals designate the same or similar parts.

Referring now to the drawings, at one end of the machine a vertical support 1 is provided for the punches P, the support including two horizontal guide bars 2 and 3 one for each end of the punches, and above the guide bar 2 a narrow die plate 4. The upper guide bar 2 and the die plate 4 may be formed integrally by slotting transversely a bar so as to provide the necessary opening between the guide and the die plate for the passage of a card after a punching operation.

Preferably, however, the die plate and 85 guide are relatively adjustable so that the opening between them may be varied.

The punches P are loosely disposed within the guide bars 2 and 3 and at their lower ends are provided with a bush or ring to 100 form on each punch a head P'. Under each punch P is disposed the extremity of a light selector bar B.

The striker S is in the form of a vertical plate mounted for reciprocation between 105 pairs of guides indicated at 5 and 6 formed on the support 1 hereinbefore referred to.

The upper part of the striker is slotted as indicated at 7 for the reception of the end 110 of a light selector bar B so that on an upstroke of the striker S the interposed bar B is struck up and also the punch P whose head overlies the interposed bar.

The slot 7 of the striker S is large enough to permit the necessary travel of the punch 115 to effect a punching operation, and the upper part S' of the striker though clear of the heads during an upstroke engages the heads on the downstroke of the striker and definitely pulls back the previously displaced punch P to normal position, and as hereafter more 120 fully explained the respective key, which causes the bar B to be interposed between the striker and the respective punch, is reset.

As clearly shown in Fig. 3 the effect of raising the striker is to obstruct the other selector bars from a movement towards their respective punches as that part of the striker S below the slot 7 stands in the path of movement of the bars. This obstruction to the selector 125

As the plate 27 is oscillated on the displacement of the actuating member R a shoulder 31 on the trip member 29 engages the tail 28 of the striker operating member 24 causing the latter to rotate about the rod 25 and cause the upward movement of the striker.

The actuating member R is provided with an adjustable abutment 32 by which the escapement mechanism of a card feeding carriage employed in the apparatus and hereafter particularly referred to, is operated when a key member is depressed causing displacement of the actuating member R the escapement mechanism including a T-shaped member 33 provided with a shoulder 34 which is engaged by the abutment 32 on the actuating member R and a nose 35.

On the rod 25 a shoulder is formed for engagement by the nose 35 and the lever 33 to effect the movement of the rod 25 and reverse movement of the finger 24 to permit or cause a downward movement of the striker.

It will be seen therefore that during the first movement of the rod R through the agency of the plate 27 and trip 29 and tail 28, the finger 24 is rocked so as to raise the striker and in the final movement of the rod R its abutment 32 presses forward the T-lever 33 of the carriage escapement mechanism and the nose 35 of the T-lever is caused to effect a retraction of the striker. The shoulder with which the nose operates may as shown in Fig. 1 be formed by a slotted sleeve member 36.

The operation of the finger 24 by the trip member 29 through the agency of the shoulder 31 and the tail piece 28 has already been explained and it will be noted that below the plate 27 is a trip pin 37 which stands in the path of movement of the trip 29 whose engaging face 29a is formed so that the cam action is effected when the trip strikes the trip pin 37 and causes an anticlockwise movement of the trip which withdraws the shoulder 31 thereof from the tail 28 of the striker lifting gear so that the latter can be reversed under the action of the nose of the lever 33 as hereinbefore explained.

The relative positions of the finger member 24 and tail 28 under operation of the trip 29 and the nose of the lever 33 are clearly shown in Figs. 5 to 8 which show the progressive positions from the lifting of the striker to the release of the striker to permit it to fall. Of these figures, Fig. 5 shows the trip 29 just going to engage the tail 28 and Fig. 6 shows the completed movement of the striker lifted, the trip just engaging the pin 37. Fig. 7 shows the deflection of the trip member from the tail 28 of the striker lifting gear by engagement of the pin 37 and the engagement of the striker lifting gear by the nose of the member 33. Fig. 8 shows the finger member 24 driven backwards in an anticlockwise

movement under the effort from the member 33.

It will be seen that the operation of the striker from the member R is effected through the trip member 29 and to prevent this trip member sticking in the position attained after engaging the trip pin 37 as shown in Fig. 7 in which position the oscillation of the plate 27 would be ineffective as regards the striker, a safety catch in the form of a J member 38 is employed. This member 38 is spring influenced and is disposed to engage the trip member in the deflected position so that on the return of the plate 27 it is caused to rock whereby on the next clockwise movement of the plate 27 the trip member must engage the trip pin 37.

Referring again to the return of the striker lifting member 24 under operation of the nose 35 of the lever 33 it will be clear that in fact the member R both lifts the striker and returns it, the nose 35 being in fact a distance piece between the abutment 32 on the member R and the sleeve member 36 on the shaft 25 so that the member R positively effects the movement of the lifting member 24 in both directions to cause the rise and fall of the striker during one direction of movement of itself.

The object of incorporating the member 35 as part of the escapement mechanism is as hereafter more fully explained to use the carriage tension to assist return of the parts after a complete reciprocation of the striker and to control unrequired lifting of the check pawl of the escapement.

Instead of using the mechanism just described with reference to Figs. 5 to 8, the striker may be carried by the sheath of an eccentric 39 as shown in Fig. 13 mounted on a rod 25a on which is carried a pinion 40 in mesh with a ratchet 41 actuated by a pawl 42 connected to the actuating member R of the striker. The pawl preferably has two operative faces 43 and 44 and the ratchet is provided with lateral abutments as for example pins 45 disposed so that the movement of the ratchet communicated to the striker through the eccentric 39 is effected by a variable effort which is at a maximum at about half travel of the ratchet. In such mechanism the face 43 first engages a pin 45 and then the effort is transmitted to the face 44 which operates at a shorter leverage, so that the final part of the step movement of the wheel will have greater force, that is to say, that the striker will be moved first of all gradually up with the selector bar and punch and during the movement of striking will be given a maximum effort which also is utilized to withdraw the striker.

In this arrangement also the member R is connected to a lever 33 of the escapement mechanism so that the tension in the carriage can be utilized to assure return of the actuated member R: for one forward move-

ment of the member R the eccentric is turned through an angle of 360° and the sheath reciprocated so that the striker S is raised and lowered.

5 The eccentric is initially set so that the actuating member commences the movement of the eccentric by applying effort at the maximum leverage. By such arrangement jarring is avoided between the operator's finger and a key when the striker is key operated.

To produce an evenness of torque in the ratchet 41 a braking lever 46 may be disposed in the path of a lug 47 on the pawl 42 so that the rocking of the member 46 under the movement of the ratchet is opposed by the pawl member itself throughout travel of the pawl and the corresponding rotation of the ratchet.

20 In an alternative construction indicated in Fig. 14 a leaf spring 46a is employed to engage against the pins 45 and so oppose the movement of the pawl 42 thereby an evenness of motion is obtained.

25 A further modified construction for operating the striker from a key is shown in Figs. 15, 16 and 17.

In this arrangement the actuating member R is in the form of a rack the teeth of which are indicated at 48 and the rack is integral 30 with the part 23 connected to the levers 21 actuated through the keys. A spindle 25a is provided as in the construction shown in Fig. 13 with an eccentric 39 and on the extremity is a pinion 40a which engages with the teeth 48 of the rack actuating member, the rack having sufficient teeth so that in one direction of movement impelled by depression of a key the rack causes a rotation of 35 the eccentric through 360° thereby the striker is lifted and withdrawn.

The rack is connected to the pinion 40a by means of what may be termed a free wheel construction to permit the return of the rack 45 without effecting the punches. Instead of the rack a toothed wheel or quadrant may be employed as will be understood in the art.

The free wheel construction is obtained by cutting the teeth of the pinion of gradually 50 increasing length from a minimum to a maximum so as to have a profile of helical form clearly shown in Figs. 16 and 17 to engage with the end face of a bush 49 carried on the rod 25a, the face of which bush is cut also in 55 the manner of a helix.

When the parts are in normal position the largest teeth of the pinion will lie in the shoulder of the helix consequently on the actuation of the rack by the depression of the key a forward movement of the rack is produced resulting in driving the pinion clockwise and the eccentric through 360° . When the key is released the rack returned under the spring pressure hereafter referred to and 60 the helical face working in opposite direction

causes the pinion 40a to be laterally displaced and disengaged from the bush 49 thereby the rack is returned without operating the striker.

The spring influence employed in returning the rack is in this construction again obtained from the escapement mechanism of the card feeding carriage the actuating member R being connected to the T lever 33 hereinbefore referred to by a rod 50 and link 51 thereby the tension of the carriage is employed to return the actuating member R to normal resetting position.

In each of the striker operating mechanisms described the T lever 33 of the escapement mechanism has been shown in adjustable relation with the actuating member R.

The carriage C has in the usual manner a carriage rack 52 and an extension 53 forming an anchorage 54 for a cable connection 55 to a spring controlled drum 56 on which the spring is indicated at 57, this being the carriage tension.

Viewing Fig. 1 the movement of the carriage to the right causes the spring 57 to be coiled and the energy conserved in the spring is expended in moving the carriage to the left step by step on the operation of the keys on the control of the escapement now to be referred to. The escapement includes the T member 33 which is pivoted at 58 on the frame of the machine and carries a pin 59 which engages with the check pawl 60 virtually pivoted at 61 on the frame of the machine. Pivoted on the frame of the machine 100 at 62 is a bell crank lever 63 at the upper end of which is formed the actuating pawl 64.

From the foregoing it will be seen that on the depression of any of the keys causing a displacement of the actuating member R that the T lever 33 is rocked and the check pawl raised out of the carriage rack 52 against the tension of spring 60a which tends to keep the check pawl in the rack and is anchored between the check pawl and the actuating pawl 64.

When the check pawl is in the carriage rack 52 movement of the rack under the carriage tension is prevented, but when it is raised then the carriage can go forward to the extent permitted. The extent of movement is governed by the actuating pawl. This pawl is pulled into the rack by a spring 65 clearly shown in Fig. 1.

It has already been explained that the movement of the actuating member R first caused the operation of the striker and then operated the lever 33, it will be clear therefore that towards the end of a downward stroke of a key that the check pawl 60 is lifted out of the rack, and premature lift avoided by the abutment of lever 33 on sleeve member 36. At the same time the actuating pawl is engaged in the rack.

In the construction shown in Fig. 1 this 130

is effected by connecting the lower arm of the bell crank 63 to a link 66 by means of a pivot pin 66a to the plate 27 of the striker actuated mechanism, which plate is connected to the actuating member R as aforesaid, consequently the actuating member R besides actuating the lever 33 and moving the check pawl also actuates the lever 63 through the agency of the plate 27 and causes the actuating pawl 64 to engage the carriage rack at the same time, all this being effected when the key is fully depressed, the carriage meanwhile being momentarily held by this actuating pawl, thereby the carriage 15 is rigidly held during the punching operation.

As soon as the key is released the check pawl flies back under the actuation of spring 60a and the carriage C has begun to move 20 under the influence of the carriage tension into the next operation so that the check pawl is ready to engage the next tooth of the carriage rack 52, at the same time the carriage actuating pawl is forced up by the force 25 of the teeth of the rack 52 so that the carriage is released to move one tooth space on to the check pawl.

It will be noted that the forcing up of the actuating pawl 64 will cause a movement of the plate 27 which in turn will cause the return of the actuating member R and eventually the resetting of the keys, thereby the tension of the carriage is employed to assure the return to normal position of the striker 35 actuating mechanism and also to reset the keys; this normal position can conveniently be referred to as reset position and therefore it can be broadly stated that the carriage tension effects the return of the parts including the keys to resetting position.

This employment of the carriage tension occurs also in the construction shown in Figs. 13 and 14 wherein the lever 63 carrying the actuating pawl is connected to the pawl 42 operating the ratchet 41 controlling the striker.

It will be noted that the pawl is slotted at 67 for the reception of a pin 68 carried by the lever 63 the arrangement being such that on the rocking of the lever 63 by the camming up of the actuating pawl 64 by the teeth of the carriage rack 52 that the ratchet 41 is reset without hindrance to the arcuate movement of the lever 63.

Further it will be noted that in the construction shown in Fig. 15 that the forcing up of the actuating pawl causes through the agency of the rod 50 and the link 51, the return of the actuating member R, in this case in the form of a rack, to resetting position, and also the resetting of the keys.

From the foregoing it will be clear that the carriage C which in manner after explained carries the cards, passes punches P and is advanced step by step for each key de-

pression and the punch actuating mechanism is carried to the escapement mechanism of the carriage so that the tension of the carriage operates to produce the return stroke of the actuating member R in a resetting of the 70 keys.

It has just been stated that when the key is fully depressed the carriage rack is momentarily held by the carriage actuating pawl. It is of interest here to note the movements of the check pawl and actuating pawl in comparison with the movements of the striker actuating the punches. The depression of a key causes the striking and withdrawal strokes of the striker, therefore, at 80 about half of the down stroke the actual act of striking the punches occurs.

Now, at this moment, the check pawl is still in engagement with the carriage rack, though perhaps slightly removed from its 85 normal position, also the actuating pawl has been partly introduced into the rack teeth, therefore, at the moment of striking the rack is actually held by the check pawl and the actuating pawl. The carriage therefore is 90 rigidly and accurately held in position during a striking operation by the arrangement of check pawl and actuating pawl and operating means operated by the key as hereinbefore set forth.

The described arrangement of check pawl and actuating pawl and their control has the advantage also that should for any reason the carriage stick in its step by step progress the actuating pawl cannot be engaged with 100 the carriage rack, hence the key cannot be depressed.

It is also of interest here to refer to the arrangement of vertical punches with sufficient weight and loosely mounted in their 105 guides so that they may fall by gravity on the withdrawal of the striker, although as hereinbefore described the striker is employed to positively return the punches after each operation.

By utilizing freely sliding punches no springs are employed, consequently the operation will become lighter as the machine becomes freer, that is to say, the machine will improve and not deteriorate as used.

Instead of the T lever 33 any bell crank or other form of lever could be employed to operate the check pawl on the depression of a key, the reason for using the T lever being to simplify the construction of skip 120 mechanism which comprises the thumb plate or finger plate 69 on the end of the T piece away from the check pawl. By depressing the finger plate 69 the T lever is rocked and the check pawl raised without moving the 125 actuating pawl lever 63; consequently the carriage C is free to skip the whole length of its travel.

The carriage may also be skipped through predetermined intervals through the agency 130

of a key 70 termed the skip key. This key is connected by a U-shaped lever 71 to a pintle 72 forming the pivot of a graduated scale bar 73 carried in a bearing member 74 on the frame of the machine, the lever 71 being clamped to the pintle 72 by the clamping piece indicated at 75, the arrangement being such that depression of the key causes the graduated scale bar 73 to be rocked and dog members 76 adjustable thereon disposed in the path of an abutment 77 carried on the extensions 53 of the carriage.

Conveniently, as shown in Fig. 1 the dogs are bifurcated members straddling the scale 73 and engaging in slots formed at the top and bottom of the scale. In practice these dogs are arranged at intervals to control in a predetermined manner the skipping of the carriage on depression of the key 70.

This movement of the scale bar is communicated by the lug 78 to a rocking lever 79 engaging a lug 80 on the T lever 33 so that the rocking of the scale by the depression of the skip key causes the lug 78 to move upwardly and to depress the clear end of the T lever and consequently the lifting of the check pawl 60.

Apart from the skipping mechanism the carriage may also be moved along at intervals of one tooth without moving a selector bar B. To this end a spacing key 81 is employed which engages on the rocking lever 19 so that the actuating member R is moved and consequently the check pawl raised and the actuating pawl simultaneously operated to control the movement of the carriage through one tooth space.

In Figs. 18 and 19 a modified form of dog is indicated at 76a. In this form of construction the dog is of plate form and recessed on its underside as indicated at 82 and the graduated scale member 73 accordingly need be slotted only on the upper side. The dog is dropped into position and gripped thereat by the spring as indicated at 83.

In a preferred construction according to the invention a carriage is employed as described and claimed in co-pending application of Arthur Thomas and Richard Fitz Power, Serial No. 384,602, filed August 9th, 1929, the carriage comprising, as shown in Figs. 20 to 23, pivoted grippers 100 in form of triangular plates pivoted at their apices indicated at 101, each gripper being controlled by a spring 102 so that one base corner is pulled towards an abutment 103 so that a card may be gripped between the grippers 100 and the abutment.

In form the carriage resembles a plate on edge and these grippers are in parallel relation therewith. The grippers are controlled by a common trip bar 104 which when moved in the direction of the arrow 105, Fig. 22, moves the grippers to operative position.

The trip bar is pivotally connected at one

end, see 104a, to a bell crank member 106 and at the leading end is associated with a spring detent 107 carrying a pin 107a passing through the carriage and provided with a spring 107b.

When the carriage has moved to the end of its travel with a card, which in Figs. 22 and 23 is indicated by the reference X, the bell crank 106 moves over a stop 108 carried on the frame of the machine. The bell crank 106 is spring controlled as indicated at 109 and is mounted with an end plate on its pivot so that as the carriage moves to the end of its travel the bell crank is deflected and wiped past the stop 108, it then becoming disposed so as to pass over the stop immediately after the return movement of the carriage commences. On the commencement of this return movement the bell crank rides over the stop and is raised, consequentially moving the trip bar in opposite direction to the arrow 105, Fig. 22, thereby causing the grippers to move away from the abutment 103 so that a card X is free to fall therefrom, the grippers being then in open position as shown in Fig. 20.

Immediately the trip bar 104 has been pressed forward its end is engaged by the detent 107 aforesaid and thereby holds the grippers open until the carriage has been brought to resetting position for the commencement of the new forward movement.

On the support 1 of the machine is a pin termed register pin 110, most clearly shown in Fig. 2, this pin being spring controlled and operable through the agency of a rocking plate 111 clearly shown in Figs. 1 and 2.

The support 1 of the punches is formed with a slot 112, see Fig. 2, which provides a positive guideway for the carriage, the part 53 of the carriage riding in the bottom of the slot.

The carriage C is perforated as indicated at 113, Figs. 20 and 22, so that the detent may be pushed away from abutment with the trip bar 104. The register pin on the support is located with regard to the punches P so that unless the carriage is pulled right home on the return journey the pin cannot pass through the carriage and engage the detent, whereas when the carriage is pushed home correctly the plate 111 can be locked and the pin 110 projected through the support 1, the perforation 113 in the carriage and on to the detent 107 which is then deflected from the abutting position with the locking bar, the latter then moving in the direction of the arrow 105, Fig. 22, under the influence of the springs 102 of the grippers so that the end of the locking bar is in overlapping relation with regard to the detent 107, see Fig. 22. In this position the grippers snap up against the abutment or against the card if one is interposed between the

grippers and the abutment 103 or the carriage.

It will be seen therefore that the carriage is so constructed that a card cannot be gripped by the carriage until the carriage is in correct relation with the punches and with the carriage is positively guided by the punches. The carriage may be provided with a plate 114 to facilitate manipulation.

10 In association with the carriage as hereinbefore described, it is preferred to form in the machine a carriage magazine and a picker mechanism operating synchronously with the carriage. To this end there is mounted between the support 1 of the punches and a support 115, a picker 116 the operating edge of the picker being parallel to the carriage so that a card engaged thereby is correctly aligned with the carriage when the grippers 20 close upon it. The picker is mounted so as to overlap the card to be removed towards the carriage for a distance slightly less than its thickness, so that in moving the card forward the card is slid towards the carriage without the picker engaging the next juxtaposed card. The cards preferably are carried on a plate or platform 117, clearly shown in Figs. 10, 24 and 25, which is spring controlled to press the pile of cards against a transparent, as for example glass, cover 118.

On the other side of the pile of cards to the picker is a throat knife 119 which extends to the card being moved by the picker so as to prevent the juxtaposed cards from being moved on to the carriage by friction during the movement of the top card of which the knife 119 is clear.

15 The picker is operated to push the card against the carriage just before the end of its travel so that the abutment 103 and grippers 100 pass over and under the longitudinal edge of a card respectively during the final movement of the carriage until it is in the correct register position before explained, thereon the projection of the pin 110 causes the operation of the grippers to grip the card so fed to the carriage.

The final movement of the carriage is effected at the expense of tensioning the spring designed to return the carriage to register position, in which position the card gripped by the carriage is just clear of the throat knife thereby any obstruction caused by the knife due to deflection in the card is avoided.

20 The picker is guided in its movements by the horizontal guideways 120 in the supports 1 and 115 before referred to, and it is operated by a rocker shaft 121 carried between these supports and provided with short rocker arms 122, one towards each end of the picker and having spherical ends which loosely engage in similar recesses formed in the upper face of the picker. By such an arrangement the picker can be moved from towards one side of the rocker shaft 121, under it, to the

other in the feeding movement. This movement is automatically effected from the carriage, the latter being provided with a shoulder 123 which during the final movements of the carriage engages one arm 124 of a bell crank pivoted at 125, see Fig. 11, the other arm 126 of which actuates a spring controlled finger 127 on the rocker shaft thereby on the final movements of the carriage the picker knife feeds forward the card to the carriage, the return of the picker being effected by the spring 128 controlling the finger 127.

25 The plate or platform 117 in association with the glass top 118 comprises a magazine for the cards, and the plate 117 forms in fact a false bottom to the magazine of which the glass 118 is the top. The plate 117 is supported by springs so that the top card is always pushed against the glass 118. To this end the plate 117 is provided along its longitudinal edges with guides 129, see Fig. 10, to receive the ends of rocking arms 130 pivotally carried at the bottom of the magazine so that the plate 117 with the arms forms in nature a cradle about the magazine springs 131.

30 The magazine is preferably at the rear formed with a hinged wall 132 the pivot of which is indicated at 133, see Fig. 24. When this wall is dropped down an opening to the magazine through which the cards may be introduced on to plate 117 is provided, and in order that the collapse of the cradle and the lowering of the platform for the reception of a pile of cards may be automatically effected when the wall 132 is dropped down, the wall is provided with cam plates 134 which bear on lugs 135 mounted on a spindle which forms the pivot of the respective rocker arm 130 so that when the hinged wall is dropped down the cams 134 at each end thereof engage the respective lugs 135 and cause the respective rocker arms 132 to be lowered so that the plate is collapsed and the plate 117 pulled down at the expense of tensioning springs 131. The cradle in collapsed position is clearly shown in Fig. 25, the magazine then being ready for charging.

35 Figs. 10 and 24 show the parts when practically the last card is leaving the magazine.

In the lowermost position of the hinged wall the cam plates 134 act as abutments between the lugs 135 aforesaid preventing the return movement of the lugs under effort of the magazine springs 131. However, when the hinged wall is raised the tension in the magazine spring is utilized to keep the lugs bearing against the plates so that the false bottom of the magazine rises to push cards to the top of the magazine as the hinged wall 125 is rocked up to close the magazine.

40 From the foregoing description it will be clear that a card is automatically taken from the top of a pile arranged in parallel relation with the carriage by the picker and de-

delivered by the picker to the carriage to be held thereby in cantilever fashion.

To assure the correct longitudinal relation of the card with the carriage at the time that it is gripped in the carriage, the magazine is formed so that one wall thereof 136 sets the card in correct position in conjunction with the picker, this wall being at right angles to the carriage.

- 10 In order to assure that the cards lie against this wall before being moved by the picker, an aligning shutter 137 is provided, see Fig. 1. This shutter is in the form of a hinged flap carried on the frame of the machine behind the punches P, being spring controlled by a spring indicated at 138 so that the flap tends to move towards the punches, the flap being operated by a stop such as 139 carried by the carriage so as to move the flap and cause it to pat the cards as the carriage is returning and just prior to the delivery of the cards by the picker to the carriage.

By such an arrangement a carriage and feeding arrangement is provided whereby the carriage accurately picks up the card at one end of its stroke. The card being gripped by the carriage and held in cantilever fashion is then traversed over the punches P and through the narrow opening between the die plate 4 and the top guide 2 of the punches P, the card moving step by step through the operating zone as the keys are depressed thereby on each depression of the key the card held in cantilever fashion is moved over the punches, the punch is operated and the card fed forward ready for the next key depression.

By such an arrangement not only does the carriage correctly pick up the card but it is accurately delivered to the punches, the carriage being guided by the carriage supports and at the end of a punching operation on a card and the commencement of the return of the carriage through the agency of the bell crank 106, the grippers are caused to release the card which drops from the carriage.

Instead of utilizing a magazine with a transparent or open top and means for removing the cards from the top, a magazine may be employed with means for removing the cards from the bottom to the carriage; such a construction is indicated in Figs. 26 and 27.

Herein a platform 140 is shown, fixed to the machine frame, on which the cards may be mounted and the cards delivered from the bottom of the pile by a picker to the carriage; the picker 116a is moved on a guide 141 passing through bearings 142 arranged transversely of the platform, and a rocker arm 143 pivoted under the platform and away from the carriage, but engaged by the carriage to move the guide 141 through its bearings and thence to the picker 116a. To this end the rocker arm 143 pivoted at 143a is by pin and

slot engagement indicated at 144 connected to a second rocking lever 145 pivoted at 145a, which in turn has a bifurcated end 146 straddling the pin 147 on the guide 141 so that as the arm 143 is moved by the shoulder 123 on the carriage returning to resetting position the picker is moved transversely to the platform 140 to bring the card to the carriage, and on the step by step forward movement of the carriage the rocker arm is gradually released allowing a movement of the picker back again to position behind the cards ready to move forward the next bottom card when the carriage is returned after the completion of the operations on the card then carried by the carriage.

The rocker arm 143 is controlled by a spring 148 which tends to keep it in engagement with the shoulder 143 of the carriage when engaged thereby, and which assures the return of the picker to operative position after the carriage has commenced its forward movement.

To assure the proper relation of the cards and the carriage in this construction a platform is provided with an abutment 136a, see Fig. 26, arranged at right angles to the carriage so that the card lying against the carriage and against the abutment is correctly given to the carriage when the carriage is in position to receive and grip the card. In this construction a flap such as 137 is also employed to assure the abutment of a card against a guide 136a previous to its reception by the carriage.

Referring to the operation of the picker in the construction illustrated in Figs. 1 and 11 a modification may be employed consisting in providing the picker with a spring controlled bell crank pivoted on the hinge line 105 of the picker the bell crank being operated by a further crank, an arm of which is disposed in the path of the carriage.

The cards on which a perforating process has been completed may be discharged in 110 suitable box conveniently disposed at the end of the machine.

Preferably, however, the machine comprises an attachment of skeleton form for the reception of the cards as they are dropped by the grippers.

A preferred arrangement is shown clearly in Fig. 1, this includes a ledge 149 on the supports 1 to each side of punches and opposed ledges 150 in the same horizontal plane on an arm 151 adjustably disposed at the side of the machine between guide stops 152 and 153, clearly shown in Fig. 10. Associated with the member 151 and the ledges 150 carried thereon are vertical guides 154 for the cards. As the carriage commences its return journey and the grippers release the cards it falls away from the carriage on to the fingers 154 and drops on to the ledges 130

149 and 150 on which the discharged cards are stacked.

The member 151 is longitudinally displaceable between guides 152 and 153 with the skeleton receptacle so formed as adapted to receive cards of various sizes, and the position of the ledges 149 and 150 with regard to the carriage may be varied vertically by disposing the longitudinal member 151 between stops 152a and 153a and stops 152 and 153 as clearly indicated in Fig. 10 by the dot and pick lines 151a showing the disposition of the longitudinal member. In this position of the longitudinal member the ledges 149 will have to be correspondingly raised, and to this end the ledges 149 are adjustably mounted on the supports 1.

A punch or punch and card feeding mechanism, as hereinbefore described, has the advantage that the punches, the keys and all the individual connections are identical so that there is merely a multiplication of a single set of parts according to the number of keys and all the parts can be cheaply and easily manufactured.

Moreover, a machine so constructed has its parts connected and adapted for operation so that a suitable distribution of load throughout the machine and to the advantage of the operator is attained.

Further, the construction of the card feeding mechanism and the punch in which the carriage is guided through the punch, assures an accurate positioning of the card if the card is fed to the carriage in the manner set out in the co-pending application of Arthur Thomas and Ritchard Fitz Power, Serial No. 384,602, filed August 9th, 1929.

What we claim is:—

1. In a key operated perforating machine the combination of a reciprocable member, operative connections between the keys and said reciprocable member, a plurality of punches, a striker for operating said punches, a positive operative connection between the striker and the punches and means connecting the striker to the reciprocable member to convert the linear movement in one direction of the reciprocable member into a reciprocating movement of the striker, whereby on depression of a key the striker causes the punches both to punch and withdraw during one movement in one direction only of the reciprocable member.

2. In a key operated perforating machine the combination of a reciprocable member, operative connections between the keys and said reciprocable member, a plurality of punches, a striker for operating said punches, heads on said punches, a bar member on the striker adapted positively to withdraw the punches, and means connecting the striker to the reciprocable member to convert the linear movement in one direction of the reciprocable member into a reciprocating movement of the

striker, whereby on depression of a key the striker causes the punches both to punch and withdraw during one movement of the reciprocable member in one direction only.

3. In a key operated perforating machine the combination of a plurality of punches, a striker for operating the punches, a positive operative connection between the striker and the punches, a plurality of light selector members, operative connections between said selector members and the keys whereby depression of a key interposes the corresponding selector member between its respective punch and the striker, a reciprocable member, operative connections between the keys and said reciprocable member, and means connecting the striker to the reciprocable member to convert the linear movement in one direction of the reciprocable member into a reciprocating movement of the striker, whereby on depression of a key the striker is actuated to cause the punches both to punch and withdraw during one movement in one direction only of the reciprocable member.

4. In a key operated perforating machine the combination of a plurality of punches, a striker for operating the punches, heads on said punches, a bar member on the striker adapted positively to withdraw the punches, a plurality of light selector members, operative connections between said selector members and the keys whereby depression of a key interposes the corresponding selector member between its respective punch and the striker, a reciprocable member, operative connections between the keys and said reciprocable member, and means connecting the striker to the reciprocable member to convert the linear movement in one direction of the reciprocable member into a reciprocating movement of the striker, whereby on depression of a key the striker is actuated to cause the punches both to punch and withdraw during one movement in one direction only of the reciprocable member.

5. In a key operated perforating machine the combination of a plurality of punches, a striker for operating the punches, a positive operative connection between the striker and the punches, a plurality of light selector members, operative connections between said selector members and the keys whereby depression of a key interposes the corresponding selector member between its respective punch and the striker, a reciprocable member, operative connections between the keys and said reciprocable member, means connecting the striker to the reciprocable member to convert the linear movement in one direction of the reciprocable member into a reciprocating movement of the striker, whereby on depression of a key the striker is actuated to cause the punches both to punch and withdraw during one movement in one direction only of the reciprocable member, and obstructor

mechanism for the selector members not interposed whereby the machine is locked against a subsequent operation until the accurate completion of the striker withdrawal stroke.

6. In a key operated perforating machine the combination of a plurality of punches, a striker for operating the punches, a positive operative connection between the striker and the punches, a plurality of light selector members, operative connections between said selector members and the keys whereby depression of a key interposes the corresponding selector member between its respective punch and the striker, a reciprocable member, operative connections between the keys and said reciprocable member, means connecting the striker to the reciprocable member to convert the linear movement in one direction of the reciprocable member into a reciprocating movement of the striker, whereby on depression of a key the striker is actuated to cause the punches both to punch and withdraw during one movement in one direction only of the reciprocable member, and a member on the striker adapted during the operation of the striker to stand in the path of the selector members not interposed, whereby subsequent movement of said selector members is prevented until the accurate completion of the striker withdrawal stroke.

7. In a key operated perforating machine the combination of a reciprocable member, operative connections between the keys and said reciprocable member, a plurality of punches, a striker for operating said punches, a positive operative connection between the striker and the punches, a bell crank lever connected to said striker, trip gear disposed between the bell crank and the reciprocable member, and means for operating said trip gear whereby the latter portion of the movement in one direction of the reciprocable member positively returns the striker after it has been moved by the first part of the movement of the reciprocable member.

8. In a key operated perforating machine, the combination of a reciprocable member, operative connections between the keys and said reciprocable member, whereby depression of a key operates the reciprocable member, a plurality of punches, a striker for operating said punches, heads on said punches, a bar member on the striker adapted positively to withdraw the punches, a bell crank lever connected to said striker, trip gear disposed between the bell crank, and the reciprocable member, and means for operating said trip gear whereby the latter portion of the movement in one direction of the reciprocable member positively returns the striker after it has been moved by the first part of the movement of the reciprocable member.

9. In a key operated perforating machine the combination of a plurality of punches, a

striker for operating the punches, a positive operative connection between the striker and the punches, a plurality of light selector members, operative connections between said selector members and the keys whereby depression of a key interposes the corresponding selector member between its respective punch and the striker, a reciprocable member, operative connections between the keys and the reciprocable member, a bell crank lever connected to the striker, trip gear disposed between the bell crank and the reciprocable member and means for operating said trip gear whereby the latter portion of the movement in one direction of the reciprocable member positively returns the striker after it has been moved by the first part of the movement of the reciprocable member.

10. In a key operated perforating machine the combination of a plurality of punches, a striker for operating the punches, a positive operative connection between the striker and the punches, a plurality of light selector members, operative connections between said selector member and the keys whereby depression of a key interposes the corresponding selector member between its respective punch and the striker, a reciprocable member, operative connections between the keys and the reciprocable member, a bell crank lever connected to the striker, trip gear disposed between the bell crank and the reciprocable member, means for operating said trip gear whereby the latter portion of the movement in one direction of the reciprocable member positively returns the striker after it has been moved by the first part of the movement of the reciprocable member, and a member on the striker adapted during the operation of the striker to stand in the path of the selector members not interposed, whereby subsequent movement of said selector members is prevented until the accurate completion of the striker withdrawal stroke.

11. In a key operated perforating machine the combination of a reciprocable member, operative connections between the keys and said reciprocable member, a plurality of punches, a striker for operating said punches, a positive operative connection between the striker and the punches, a bell crank lever connected to said striker, a trip in the form of a second bell crank, said second bell crank being pivoted on one arm of a third bell crank coaxial with but independent of the first bell crank device lifting the striker, said second bell crank including a shoulder engaging the bell crank lifting device for the striker, said third bell crank being connected to the reciprocable member, an abutment for tripping said second bell crank after the reciprocable member has bodily moved said second bell crank sufficiently to actuate the striker lifting bell crank whereby the striker is automatically released from its lifting gear after a punching operation and a safety

catch actuating said second bell crank on the return movement of the actuating member to reset the second bell crank for the next striking and perforating operation.

12. In a key operated perforating machine the combination of a plurality of punches, a striker for operating the punches, a positive operative connection between the striker and the punches, a plurality of light selector members, operative connections between said selector members and the keys whereby depression of a key interposes the corresponding selector member between its respective punch and the striker, a reciprocable member, operative connections between the keys and said reciprocable member, 70 means connecting the striker to the reciprocable member to convert the linear movement in one direction of the reciprocable member into a reciprocating movement of the striker, whereby on depression of a key the striker is actuated to cause the punches both to 75 punch and withdraw during one movement in one direction only of the reciprocable member, a key action carriage, tension means to advance said carriage, escapement mechanism for the carriage and an operative connection between said escapement mechanism and the reciprocable member whereby the escapement mechanism is actuated on depression of a key and the tension of the carriage 80 serves to assist the return of the reciprocable member.

13. In a key operated perforating machine to the reciprocable member, an abutment for tripping said second bell crank after the reciprocable member has bodily moved said second bell crank sufficiently to actuate the striker lifting bell crank, whereby the striker 85 is automatically released from its lifting gear after a punching operation and a safety catch actuating said second bell crank on the return movement of the actuating member to reset the first bell crank for the next striking and perforating operation.

14. In a key operated perforating machine the combination of a reciprocable member, a key action carriage, tension means to advance said carriage, operative connections between the keys and said reciprocable member, a plurality of punches, a striker for operating said punches, a positive operative connection between the striker and the punches, means connecting the striker to the reciprocable member to convert the linear movement in one direction of the reciprocable member into a reciprocating movement of the striker, whereby on depression of a key the striker causes the punches both to punch and withdraw during one movement of the reciprocable member in one direction only, escapement mechanism for the carriage, and an operative connection between said escapement mechanism and the reciprocable member whereby the escapement mechanism is actuated on depression of a key and the tension of the carriage serves to assist the return of the reciprocable member.

15. In a key operated perforating machine the combination of a reciprocable member, a key action carriage, tension means to advance said carriage, operative connections between the keys and the reciprocable member, a plurality of punches, a striker for operating said punches, a positive operative connection between the striker and the punches, a plurality of light selector members, operative connections between said selector members and the keys

whereby depression of a key interposes the corresponding selector member between its respective punch and the striker, a reciprocable member, operative connections between the keys and said reciprocable member, 70 means connecting the striker to the reciprocable member to convert the linear movement in one direction of the reciprocable member into a reciprocating movement of the striker, whereby on depression of a key the striker is actuated to cause the punches both to 75 punch and withdraw during one movement in one direction only of the reciprocable member, a key action carriage, tension means to advance said carriage, escapement mechanism for the carriage and an operative connection between said escapement mechanism and the reciprocable member whereby the escapement mechanism is actuated on depression of a key and the tension of the carriage 80 serves to assist the return of the reciprocable member.

16. In a key operated perforating machine the combination of a reciprocable member, a key action carriage, tension means to advance said carriage, operative connections between the keys and the reciprocable member, a plurality of punches, a striker for operating said punches, a positive operative connection between the striker and the punches, a bell crank lever connected to the striker, trip gear 100

105

- disposed between the bell crank and the reciprocable member, means for operating said trip gear, whereby the latter portion of the movement in one direction of the reciprocable member positively returns the striker after it has been moved by the first part of the movement of the reciprocable member, escapement mechanism for the carriage, and an operative connection between said escapement mechanism and the reciprocable member whereby the escapement mechanism is actuated on depression of a key and the tension of the carriage serves to assist the return of the reciprocable member.
- 15 17. In a key operated perforating machine the combination of a plurality of punches, a striker for operating the punches, a positive operative connection between the striker and the punches, a plurality of light selector members, operative connections between said selector members and the keys whereby depression of a key interposes the corresponding selector member between its respective punch and the striker, a reciprocable member, operative connections between the keys and the reciprocable member, a bell crank lever connected to the striker, trip gear disposed between the bell crank and the reciprocable member, means for operating said trip gear whereby the latter portion of the movement in one direction of the reciprocable member positively returns the striker after it has been moved by the first part of the movement of the reciprocable member, a key action carriage, tension means to advance said carriage, escapement mechanism for said carriage, and an operative connection between said escapement mechanism and the reciprocable member whereby the escapement mechanism is actuated on depression of a key, said escapement mechanism including check and actuating pawls cooperating with the carriage rack and delay means connecting said reciprocable member and the check pawl whereby the striker is operated as a preliminary to the release of said check pawl from the carriage rack, whereby the punching operation is effected while the carriage is positively held against movement in either direction by the check and actuating pawls, and the tension of the carriage assists the return of the reciprocable member.
- 20 18. In a key operated perforating machine the combination of a reciprocable member, a key action carriage, tension means to advance said carriage, operative connections between said carriage and said reciprocable member, a plurality of punches, a striker for operating said punches, a positive operative connection between the striker and the punches, means connecting the striker to the reciprocable member to convert the linear movement in one direction of the reciprocable member into a reciprocating movement of the striker, whereby on depression of a key the striker causes the punches both to punch and withdraw during one movement of the reciprocable member in one direction only, escapement mechanism for the carriage, and an operative connection between said escapement mechanism and the reciprocable member whereby the escapement mechanism is actuated on depression of a key, said escapement mechanism including check and actuating pawls co-operating with

the carriage rack and delay means connecting said reciprocable member and the check pawl whereby the striker is operated as a preliminary to the release of said check pawl from the carriage rack, whereby the punching operation is effected while the carriage is positively held against movement in either direction by the check and actuating pawls, and the tension of the carriage assists the return of the reciprocable member.

25 19. In a key operated perforating machine, the combination of a reciprocable member, a key action carriage, tension means to advance said carriage, operative connections between the keys and the reciprocable member, a plurality of punches, a striker for operating said punches, a positive operative connection between the striker and the punches, a bell crank lever connected to the striker, trip gear disposed between the bell crank and the reciprocable member, means for operating said trip gear whereby the latter portion of the movement in one direction of the reciprocable member positively returns the striker after it has been moved by the first part of the movement of the reciprocable member, escapement mechanism for the carriage, and an operative connection between said escapement mechanism and the reciprocable member, whereby the escapement mechanism is actuated on depression of a key, said escapement mechanism including check and actuating pawls cooperating with the carriage rack and delay means connecting said reciprocable member and the check pawl whereby the striker is operated as a preliminary to the release of said check pawl from the carriage rack, whereby the punching operation is effected while the carriage is positively held against movement in either direction by the check and actuating pawls, and the tension of the carriage assists the return of the reciprocable member.

30 In testimony whereof we hereby affix our signatures.

ARTHUR THOMAS.
RICHARD FITZ POWER.
